PNEUMATIC RIFLE

Nathan H. Price, Birmingham, Ala., assignor of
one-half to Grady Gillespie, Birmingham, Ala.

Application August 14, 1934, Serial No. 739,802

8 Claims. (Cl. 124—8)

The invention relates to a pneumatic rifle and more especially to a safety breech loading repeater air gun.

The primary object of the invention is the provision of a rifle or gun of this character, wherein shot from a magazine can be successively fed with safety against premature discharge from the discharge barrel at its breech end for repeating action and the discharge of the shot being pneumatically controlled, the rifle or gun in its construction being of novel form.

Another object of the invention is the provision of a rifle or gun of this character, wherein the pumping of the same may be had with safety against accidental discharge of shot during the pumping period and in which is involved the magazines for the storage of shot, one being adapted to feed the shot to a cylinder which is revolvably supported at the breech end of the discharge barrel, so that successively the shot can be brought into discharging position at the breech end of said barrel and after each shot, upon discharge, the barrel is left empty so that the pumping of the gun may be accomplished without liability of accidental discharge of a load therefrom, the pumping action being smooth, with assurance of maximum compression, while the trigger is safe due to its design and the location of its pivot pin which is so placed that any forward pressure of the firing plunger tends to tighten it and said trigger released under an even pressure at all times.

A further object of the invention is the provision of a rifle or gun of this character wherein the action of the firing plunger which strikes the release valve is novel in that it instantly releases the full volume and pressure of air in the compression chamber directly against the shot to be discharged.

A still further object of the invention is the provision of a rifle or gun of this character which is comparatively simple in construction, thoroughly reliable and efficient in its operation, compact, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a side elevation of a rifle or gun constructed in accordance with the invention.

Figure 2 is an enlarged fragmentary vertical longitudinal sectional view.

Figure 3 is a fragmentary top plan view partly in section.

Figure 4 is a sectional view on the line 4—4 of Figure 2 looking in the direction of the arrows.

Figure 5 is a sectional view on the line 5—5 of Figure 2 looking in the direction of the arrows.

Figure 6 is a perspective view of the trigger.

Figure 7 is a fragmentary diagrammatic view showing in detail the magazine closure clip.

Similar reference characters indicate corresponding parts throughout the several views in the drawing.

Referring to the drawing in detail, A designates generally a portion of the rifle or gun stock which may be of conventional style and upon which is mounted the gun body, the rear portion of which constitutes the breech 10, while the forward portion forms a pump including a cylinder 11 which, at the lowermost external portion, has formed therewith a lug 12, the same fitting correspondingly shaped depression or recess in the stock A and from without the latter is passed a screw 13 which is threaded into the lug 12, so that these parts, namely, the stock and the body, will be detachably fitted with each other.

Superimposed upon the cylinder 11 is the discharge barrel 14, these being aligned, and at opposite sides of this barrel are the tubular magazines 15 and 16, respectively, extended parallel one with the other. The magazines 15 and 16 are of less length than the barrel 14, the latter and the said magazines, at their inner ends, being in confronting relation to a revolving feed cylinder 17 having the rearwardly tapered shot receiving openings 18 arranged uniformly spaced from each other and in a circular trend for successive registration with the inner ends of the barrel 14 and the magazines 15 and 16, respectively. The cylinder 17 is rotatable upon a forwardly directed tubular extension 19 of the breech end 10 which extends into the cylinder 11 and at its free end is formed with a knife edge valve seat 20.

Fitting the outer end of the cylinder 11 is a packing gland 21 surrounding a plunger 22 having at its outer end the knob-like hand grip 23 which is outside of said cylinder 11, while at the inner end of this plunger 22 is a piston 24 which operates within the cylinder 11 for air pumping purposes. Arranged within the cylinder 11 is a

block 25 dividing the said cylinder to provide at its inner end a compressed air chamber 26, the block 25 being formed with an internal valve seat 27 about a port or passage 28 establishing communication between the pumping side of the cylinder 11 and the compressed air chamber 26. Slidably fitted in the block 25 is a valve 29 normally engaged with said seat 27, while engageable with the valve seat 20 of the tubular extension 19 is a valve 30, the same being carried by a push pin 31. This pin 31 fits within a central bore constituting an air passage 32 from the chamber 28 to a breech discharge nozzle 33 common to a single hole 18 in the revolving cylinder 17, so that compressed air will deliver a shot from this hole into the barrel 14 for the discharge of said shot therefrom.

Surrounding the plunger 22 is a coiled cushioning spring 34 active on the outward stroke of said plunger, the cylinder 11 having the piston 24 therein being provided with the air inlet port or vent 35 opening to the atmosphere.

Interposed between the valves 29 and 30 is a coiled tensioning spring 36 which is seated against retaining lugs 37 and 38, respectively, for the holding of said spring aligned with said valves and this spring functions to normally seat the said valves 29 and 30, as should be apparent from Figure 2 of the drawing.

Formed in the rear end of the breech 10 is a hammer chamber 39 having fitted therein a slideable hammer head 40 provided with a cocking stem 41 which extends through a cap 42 fitting the breech 10 and closing the outer end of the chamber 39, the same being provided with the knob-like hand grip 43 at its outer end, while surrounding this stem 41 is a coiled expansion spring 44 to force the hammer head 40 inwardly in the chamber 39 for actuating the push pin 31 for the unseating of the valve 30 so that compressed air within the chamber 26 can flow through the nozzle 33 for the discharge of a shot from the cylinder 17 and the barrel 14, the chamber 26 being supplied with compressed air by actuating the piston 24, as should be obvious.

At the breech end 10 and formed in the stock A is a trigger slot 45 for a trigger 46 having the bell crank-like hanger fork 47 pivoted at 48 to a bearing 49 formed on the breech end 10 and this trigger 46 locks the hammer head 40 in cocked position within the chamber 39. The trigger 46 is forced to cocking position by a leaf spring 49 active upon said trigger, the hammer head 40 being moved to cocking position manually by pulling outwardly upon its stem 41 by hand. The pump plunger 22 is manually operated.

Arranged within the inner end of the magazine 16 is a spring pressed snapping latch or keeper pin 50 which engages with a confronting hole 18 in the cylinder 17 so as to latch the said cylinder for the aligning of one of its holes 18 with the barrel 14 and another of its holes 18 with the magazine 15 so that shot contained within the latter can be delivered into the cylinder 17 singly and the delivery of a shot from said cylinder under compressed air to the barrel 14 for the discharge of said shot therefrom, the compressed air being fed through the nozzle 33 to the barrel 14, as hereinbefore set forth.

Located upon the magazines 15 and 16 is an adjustable sight 51 cooperating with the stationary sights 52 and 53, respectively, upon the barrel 14.

Mounted as usual upon the stock A is a trigger guard 54.

Removably and swingingly carried at the forward end of the magazine 16 is a closure clip 55 which constitutes a dual closure for both magazines 15 and 16 at their outer ends, it being apparent that when swinging the clip 55 away from the magazine 15, at its outer end, shot may be placed within this magazine and to enable convenient loading of the cylinder 17 the said magazine 15 next to the cylinder is provided with a slot 56 which permits of the urging of the shot into the holes or openings 18 in said cylinder from the magazine 15 and the shot fed to the said cylinder 17 cannot drop out of the holes or openings 18 therein in a rearward direction, while the abutting portions of the gun body and the stock at the front side of the said cylinder 17 will assure the retention of the shot within the holes or openings 18 therein.

It will be apparent that when a shot has been discharged from the barrel 14 the same remains empty and thus an accidental discharge of shot from the rifle or gun will be presented during the pumping of the said rifle or gun for the pneumatic operation thereof.

The nozzle 33 is removably fitted in the breech end 10 of the gun body to enable the cleaning thereof or for repair purposes. It also will be obvious that the parts of the rifle or gun are readily demountable for free accessibility.

The magazine 16 may be utilized for the storage of shot augmenting the supply in the magazine 15, but such shot as contained within the magazine 16 must necessarily be transferred to the magazine 15 for the feed of such shot therefrom to the cylinder 17.

The valves 29 and 30 carry the packings 57 and 58, these being renewable when the occasion requires, to avoid possibility of leakage of compressed air into the chamber 26.

On the uncocking of the hammer head 40 a push pin 31 will be acted upon to unseat the valve 30 and compressed air within the chamber 26 will flow through the passage 32 and nozzle 33 to the discharge barrel 14 for the sending of a shot as contained within the opening or hole 18 in the cylinder 17 confronting said barrel, the compressed air being delivered directly to the barrel for the discharge of the shot therefrom. The cylinder 17 is manually revolved for repeating action of the rifle or gun.

What is claimed is:

1. A rifle of the kind described comprising a gun stock, a gun body carried by the stock and having a rear portion forming a breech and a forward portion forming a pump including a cylinder, a discharge barrel superimposed upon said cylinder, tubular magazines arranged at opposite sides of the barrel and of less length than the latter, a revolving feed cylinder confronting the said barrel and magazines at their rear ends and having rearwardly tapered shot receiving openings uniformly spaced from each other in a circular trend for register with the said barrel and magazines, a tubular extension on the breech and rotatably supporting the feed cylinder, a block arranged within the pump to provide a compressed air chamber adjacent the breech and having an opening to the pumping side of said pump, an air pumping plunger fitted in said pump cylinder at the pumping side thereof, a valve seated in said block to close the opening therein, a breech nozzle leading from said tubular extension for discharging compressed air through the revolving feed cylinder into the dis-

- charge barrel, a push pin working in the tubular extension and having a valve for closing communication between the compressed air chamber and said nozzle, an expansion spring between the 5 said valves to normally hold the same seated, a hammer acting upon said push pin and spring controlled, and a trigger cocking said hammer.
2. A rifle of the kind described comprising a gun stock, a gun body carried by the stock and 10 having a rear portion forming a breech and a forward portion forming a pump including a cylinder, a discharge barrel superimposed upon said cylinder, tubular magazines arranged at opposite sides of the barrel and of less length than the latter, a revolving feed cylinder confronting the said barrel and magazines at their rear ends and having rearwardly tapered shot receiving 15 openings uniformly spaced from each other in a circular trend for register with the said barrel and magazines, a tubular extension on the breech and rotatably supporting the feed cylinder, a block arranged within the pump to provide a compressed air chamber adjacent the breech and having an opening to the pumping side of 20 said pump, an air pumping plunger fitted in said pump cylinder at the pumping side thereof, a valve seated in said block to close the opening therein, a breech nozzle leading from said tubular extension for discharging compressed air through the revolving feed cylinder into the discharge barrel, a push pin working in the tubular extension and having a valve for closing communication between the compressed air chamber and said nozzle, an expansion spring between 25 the said valves to normally hold the same seated, a hammer acting upon said push pin and spring controlled, a trigger cocking said hammer, a pull stem on said hammer for manually retreating the same, a latch means in one of the magazines 30 and engageable with the feed cylinder to frictionally latch the same in set position, and a closure clip bridging the discharge barrel and swingingly supported to close the outer ends of the said magazines. 35
3. A rifle of the kind described comprising a gun stock, a gun body carried by the stock and having a rear portion forming a breech and a forward portion forming a pump including a cylinder, a discharge barrel superimposed upon 40 said cylinder, tubular magazines arranged at opposite sides of the barrel and of less length than the latter, a revolving feed cylinder confronting the said barrel and magazines at their rear ends and having rearwardly tapered shot receiving 45 openings uniformly spaced from each other in a circular trend for register with the said barrel and magazines, a tubular extension on the breech and rotatably supporting the feed cylinder, a block arranged within the pump to provide a compressed air chamber adjacent the breech and having an opening to the pumping side of 50 said pump, an air pumping plunger fitted in said pump cylinder at the pumping side thereof, a valve seated in said block to close the opening 55 therein, a breech nozzle leading from said tubular extension for discharging compressed air through the revolving feed cylinder into the discharge barrel, a push pin working in the tubular extension and having a valve for closing communication between the compressed air chamber and said nozzle, an expansion spring between 60 the said valves to normally hold the same seated, a hammer acting upon said push pin and spring controlled, a trigger cocking said hammer, a pull 65 stem on said hammer for manually retreating the same, a latch means in one of the magazines and engageable with the feed cylinder to frictionally latch the same in set position, a closure clip bridging the discharge barrel and swingingly supported to close the outer ends of the said magazines, and an adjustable sight slidably connected with the magazines and properly arranged with the barrel. 70
4. A rifle of the kind described comprising a gun stock, a gun body carried by the stock and 75

gun stock, a gun body carried by the stock and having a rear portion forming a breech and a forward portion forming a pump including a cylinder, a discharge barrel superimposed upon said cylinder, tubular magazines arranged at opposite sides of the barrel and of less length than the latter, a revolving feed cylinder confronting the said barrel and magazines at their rear ends and having rearwardly tapered shot receiving 10 openings uniformly spaced from each other in a circular trend for register with the said barrel and magazines, a tubular extension on the breech and rotatably supporting the feed cylinder, a block arranged within the pump to provide a 15 compressed air chamber adjacent the breech and having an opening to the pumping side of said pump, an air pumping plunger fitted in said pump cylinder at the pumping side thereof, a valve seated in said block to close the opening 20 therein, a breech nozzle leading from said tubular extension for discharging compressed air through the revolving feed cylinder into the discharge barrel, a push pin working in the tubular extension and having a valve for closing communication 25 between the compressed air chamber and said nozzle, an expansion spring between the said valves to normally hold the same seated, a hammer acting upon said push pin and spring controlled, a trigger cocking said hammer, a pull 30 stem on said hammer for manually retreating the same, a latch means in one of the magazines and engageable with the feed cylinder to frictionally latch the same in set position, a closure clip 35 bridging the discharge barrel and swingingly supported to close the outer ends of the said magazines, an adjustable sight slidably connected with the magazines and properly arranged with the barrel, fore and aft stationary sights on said barrel, and a knobbed stem operable exteriorly of the pump cylinder and engaged with said plunger.

7. A rifle of the kind described comprising a

gun stock, a gun body carried by the stock and having a rear portion forming a breech and a forward portion forming a pump including a cylinder, a discharge barrel superimposed upon said cylinder, tubular magazines arranged at opposite sides of the barrel and of less length than the latter, a revolving feed cylinder confronting the said barrel and magazines at their rear ends and having rearwardly tapered shot receiving 50 openings uniformly spaced from each other in a circular trend for register with the said barrel and magazines, a tubular extension on the breech and rotatably supporting the feed cylinder, a block arranged within the pump to provide a compressed air chamber adjacent the breech and having an opening to the pumping side of said pump, an air pumping plunger fitted in said pump cylinder at the pumping side thereof, a valve seated in said block to close the opening therein, a breech nozzle leading from said tubular extension for discharging compressed air through the 55 revolving feed cylinder into the discharge barrel, a push pin working in the tubular extension and having a valve for closing communication between the compressed air chamber and said nozzle, an expansion spring between the said valves to normally hold the same seated, a hammer acting upon said push pin and spring controlled, a trigger cocking said hammer, a pull stem on said hammer for manually retreating the same, a latch means in one of the magazines and engageable with the feed cylinder to frictionally latch the same in set position, a closure clip bridging the discharge barrel and swingingly supported to close the outer ends of the said magazines, an adjustable sight slidably connected with the 60 magazines and properly arranged with the barrel, fore and aft stationary sights on said barrel, a knobbed stem operable exteriorly of the pump cylinder and engaged with said plunger, and a cushioning spring carried by said last-named stem.

NATHAN H. PRICE.

rel, a push pin working in the tubular extension and having a valve for closing communication between the compressed air chamber and said nozzle, an expansion spring between the said valves to normally hold the same seated, a hammer acting upon said push pin and spring controlled, a trigger cocking said hammer, a pull stem on said hammer for manually retreating the same, a latch means in one of the magazines and engageable with the feed cylinder to frictionally latch the same in set position, a closure clip bridging the discharge barrel and swingingly supported to close the outer ends of the said magazines, an adjustable sight slidably connected with the magazines and properly arranged with the barrel, fore and aft stationary sights on said barrel, and a knobbed stem operable exteriorly of the pump cylinder and engaged with said plunger.

8. A rifle of the kind described comprising a gun stock, a gun body carried by the stock and having a rear portion forming a breech and a forward portion forming a pump including a cylinder, a discharge barrel superimposed upon said cylinder, tubular magazines arranged at opposite sides of the barrel and of less length than the latter, a revolving feed cylinder confronting the said barrel and magazines at their rear ends and having rearwardly tapered shot receiving 10 openings uniformly spaced from each other in a circular trend for register with the said barrel and magazines, a tubular extension on the breech and rotatably supporting the feed cylinder, a block arranged within the pump to provide a compressed air chamber adjacent the breech and having an opening to the pumping side of said pump, an air pumping plunger fitted in said pump cylinder at the pumping side thereof, a valve seated in said block to close the opening therein, a breech nozzle leading from said tubular extension for discharging compressed air through the 15 revolving feed cylinder into the discharge barrel, a push pin working in the tubular extension and having a valve for closing communication between the compressed air chamber and said nozzle, an expansion spring between the said valves to normally hold the same seated, a hammer acting upon said push pin and spring controlled, a trigger cocking said hammer, a pull stem on said hammer for manually retreating the same, a latch means in one of the magazines and engageable with the feed cylinder to frictionally latch the same in set position, a closure clip bridging the discharge barrel and swingingly supported to close the outer ends of the said magazines, an adjustable sight slidably connected with the 20 magazines and properly arranged with the barrel, fore and aft stationary sights on said barrel, a knobbed stem operable exteriorly of the pump cylinder and engaged with said plunger, and a cushioning spring carried by said last-named stem.
